C. W. WEYER

UNITED STATES PATENT OFFICE.

ARISTOTE MAVROGENIS, OF MILWAUKEE, WISCONSIN.

WIRELESS APPARATUS.

Application filed December 26, 1923. Serial No. 682,666.

To all whom it may concern:

Be it known that I, ARISTOTE MAVROGENIS, a subject of Greece, and resident of Milwaukee, in the county of Milwaukee and

5 State of Wisconsin, have invented certain new and useful Improvements in Wireless Apparatus; and I do hereby declare that the following is a full, clear, and exact description thereof.

10 This invention relates to electron discharge devices, and is particularly directed to an apparatus for energizing the anodes and cathodes from an alternating current source.

15 In devices of this nature when used for wireless reception, it has been the usual practice to energize the cathodes and anodes with dry batteries or storage batteries and the frequency with which they have to be inspect-

20 ed and attended to, and recharged or renewed, detracts materially from the uniform application or use of this type of apparatus. Efforts have been made to use alternating current by rectifying and by subsequently

25 filtering but with the usual type of apparatus of this nature the alternating current hum or ripple is manifest and materially detracts from the serviceability of the apparatus. Further, devices of this nature have 30 heretofore been cumbersome and elaborate, and consequently the difficulty of using them and the expense has precluded uniform adaption to wireless reception.

This invention is designed to overcome the 35 above noted defects and the primary objects of such invention are to provide a wireless receiving apparatus in which the cathodes and anodes are energized from alternating current without any resulting hum or disturbance from such energization, and to provide a unitary device which combines in itself both the rectifier and the filter as well as the detector or amplifier.

Further objects are to provide an electron 45 discharge device in which equipotential cathodes are employed and are associated with rectifiers, filters, and detectors or amplifier, in which substantially all the energy supplied for heating the cathode is 50 usefully employed and losses are reduced to a minimum, in which a low plate impedance is attained, in which a high efficiency is attained, and in which smooth and reliable operation is assured, so that the device may be

most efficiently adjusted and may be maintained at such adjustment, or may be quickly reestablished from day to day with the assurance that similar results will always be attained.

Further objects are to provide a unitary 60 device embodying a rectifier, a detector, and a filter, all of which are operated from commercial alternating current lines, in which the rectified current is absolutely free from fluctuations and may be used not only in the 65 unitary device, but also for energizing auxiliary devices such, for instance, as other tubes and the electromagnet of loud speakers or similar devices.

Further objects are to provide a receiving 70 device for radio signals whereby alternating current may be employed for actuating all portions of the apparatus, and to provide a device which may be expeditiously employed and which is highly efficient. 75

Embodiments of the invention are shown in the accompanying drawings, in which:—

Figure 1 is a diagrammatic view of one form of the apparatus.

Figure 2 is a perspective view of a tube 80 constructed in accordance with the disclosure of Figure 1.

Figures 3 and 4 are diagrammatic views showing further forms of the invention.

Figures 1 and 2 showing one form of the 85 invention will now be described first with reference to Figure 1.

The unitary device comprises an evacuated vessel 1 which is exhausted to a high degree. Within this vessel a rectifier filament 90 2 is positioned in close proximity to a plate 3 which serves both as the anode of the rectifier and as the cathode of the detector or amplifier. Adjacent this plate 3 and upon the opposite side thereof from the 95 filament 2 a grid 4 is positioned, and beyond the grid the plate 5 of the detector or amplifier is located. The side of the plate 3, towards the plate 5, is coated with material having low electron affinity such, for 100 instance, as barium, thorium, strontium, calcium or similar oxides, and, if desired, the filament 2 may be similarly coated. A second filament 6 is positioned within the tube and is preferably coated with a material of high electron affinity such, for 105 instance, as nickelous oxide. Adjacent this filament and in a position to be heated there-

by a plate 7 is positioned and is coated on its side toward the filament 6 with nickelous or similar dielectric oxide. On its opposite side, however, the plate is coated 5 with a material of low electron affinity such as that previously described. On this last mentioned side of the plate 7, the anode 8 of the current limiting or wave filter portion of the device is positioned. It is preferable to provide a shield 9 of mica or similar material or of metal coated with nickelous oxide so as to divide the tube loosely into two portions.

A transformer having its primary 10 connected across the alternating current mains 11 is provided with a step-up secondary 12 and with a step-down secondary winding 13. Either or both of these windings may be provided with a plurality of taps in a well known manner. One end of the high volted secondary is connected through a choke coil 14 with the anode 8 of the current limiting device or filter. Small capacity condensers 15 and 16 may be connected to opposite sides 20 of the choke coil 14 and may have their other terminals joined by means of conductor 17. From this conductor a second conductor 18 leads to the plate 3. The other end of the step-up secondary 12 is connected directly 25 with the step-down secondary 13, and this point of union of the two secondaries is connected by means of conductor 19 with one side of the filament 2. It is to be noted that the filaments 2 and 6 are joined by 30 means of conductor 20. One end of the filament 6 is connected through a suitable rheostat 21 with the outer terminal of the step-down winding 13 of the transformer. Thus the rheostat 21 and the two filaments are 35 placed in a local circuit and are connected in series with the secondary 13 and may be simultaneously regulated by the rheostat 21 although, obviously, a parallel connection with independent or with a common rheostat might be employed or the filament circuits may be wholly independent.

The equipotential cathode 7 of the current limiting device or filter is connected to the positive end of a high resistance 22. The negative end of this resistance is connected 50 by means of conductor 23 with the equipotential electrode 3. The negative side of the resistance 22 is connected by means of conductor 24 with the movable coils of the loud speaker 25 of standard construction. The other side is connected by means of conductor 25 with the plate 5 of the detector. If desired, an auxiliary resistance 26 may be bridged between the slidable contact 27 55 and the negative end of the resistance 22 for a purpose hereinafter to appear. The negative side of the resistance 22 is connected by means of conductor 28 with the field coils or constant current coils of the loud speaker 25 and the other side of such coils

is connected to a slidable contact 29 cooperating with the resistance 22 so that the exact potential needed may be secured.

The grid 4 is connected through a grid condenser 30 bridged by a suitable leak resistance with one side of the secondary 31 of a loose coupler,—the other side of the secondary 31 of the coupler is connected to the plate 3. A variable condenser 32 is bridged across the coil 31, as shown, and is used for tuning purposes. The primary 33 of the loose coupler may have one end grounded and the other end connected either to the antenna 34 or else connected thereto through the medium of a variable condenser 35. Obviously, a loop could be substituted for the antenna and ground if desired.

It is to be noted that the filter or thermionic current limiting device is a high vacuum device and is so organized that its action is free from ionization. The operation of the apparatus is as follows:—The filaments 2 and 6 are heated to the desired extent and controlled by the rheostat 21. Assuming that a positive pulse passes to the condenser 16, this positive pulse repels a positive charge from the other side of the condenser up the wire 18 to the electrode 3 and passes to the filament 2 and from thence by means of conductor 19 back to the other side of the transformer. This leaves the condenser 15 charged, and when the voltage at the left hand end of the transformer winding 12 drops, the condenser discharged through the choke coil 14 to the plate of the filter and from thence to the cathode 7 thereof. From this point the current passes to the positive terminal of resistance 22 through such resistance along conductor 23, conductor 18 and conductor 17 to the other side of the condenser. A negative pulse from the left hand end of the transformer will pass to condenser 15 repelling the negative charge along the wire 17, the wire 18 to the electrode 3. Such pulse will be stopped by the rectifier. The filter maintains an absolutely steady value of current through the resistance 22 as it is worked beyond its saturation point in its plate-voltage, plate-current characteristic. The condensers 15 and 16 and the choke coil 14 aid in the suppression of any pulsations in the current flow.

It is to be noted that the filament 2 freely gives out electrons thus causing the plate 3 and the filament 2 to act in the usual capacity of rectifier. The equipotential cathode 7 and the plate 8 act as a current limiting device, as described in my copending application for rectifiers, filed July 18, 1923, Serial Number 652,266.

If desired, the side of the equipotential cathode 7 towards the plate, may be coated with a lower electron affinity oxide, as previously described.

To state the action of the current limiting device, in other words, as described in my copending application, it may be stated that current from the rectifier is supplied to this wave filter or current limiting device at such voltage as to pass the saturation point or bend in its plate-voltage current characteristic curve, thus the current passed between the plate and the equipotential cathode 7 is constant and is independent of the variations in the impressed voltage.

The current through the unitary resistance 22 is constant and the exact voltage, which it is desired for the other portions 15 of the system, may be obtained by adjusting the variable point connectors 27 and 29,-- the connector 27 controlling the voltage impressed on the detector plate 5 through the movable coil of the loud speaker, or receiver.

It is to be noted that the auxiliary resistance 27 provides a bypass around the lower portion of the unitary resistance 22 so as to permit any variation in current in the circuit of the plate 5, when such circuit is in 25 operation during radio reception, to pass through this resistance as well as through a portion of the unitary resistance so that such unitary resistance is not subjected to appreciable fluctuations in current value 30 even when wireless signals are received.

It is to be noted in connection with the rectifier composed of the filament 2 and electrode 3, that such electrode 3 serves a double purpose. It acts not only in the capacity of the electrode of a rectifier but also as the equipotential cathode of a detector. The plate 5 is spaced from such equipotential cathode and a grid 4 is located between these two elements,—the grid and cathode being 40 connected to the receiving system in any desired manner.

Figure 2 shows a further practical form in which the composite bulb may be made. In this figure the same reference characters 45 designate the essential parts of the apparatus, as are used in Figure 1. The bulb 1 is a high vacuum tube and is provided with a central pillar 36 which supports a quartz, porcelain, or other oval shaped or elongated member 37. This member may be provided with two main portions and with a groove 50 within which the mica or other partition 9 is positioned. These two main sections of the member 37 are preferably provided with 55 spiral grooves within which the filaments 2 and 5 are wound, such filaments being conveniently themselves, of spiral formation to secure the requisite length for direct energization from 110 volt mains, if desired, instead of from an auxiliary secondary or step-down secondary or a transformer, as described in connection with Figure 1. The lower portion of the apparatus constitutes 60 the rectifier and detector or amplifier. The

electrode 3 is spaced from the filament 2 65 and carried in any suitable manner as, for instance, upon flanges formed upon the member 37, as illustrated in Figure 2. Outside of the electrode 3 the grid 4 is positioned and may comprise a spiral wire winding 70 4 which is carried upon the vertical arms 38 of a wire frame. This wire frame may have upper and lower parallel closed members or supporting rings 39 which are carried by supports 40. These supports form 75 the connections for the grids, as shown in Figure 2. Outside of the grid the plate 5 is positioned and is carried by rigid wire arms 41 supported by a glass pillar 42. This glass pillar is hollow and carries a 80 central conductor 43 which is electrically distinct from the supporting arms 41. The plate 5 is connected to the outside terminals of the apparatus and also is partially supported by the member 44. 85

The upper portion of the apparatus is the wave filter or current limiting portion of the device. It is formed in a somewhat similar manner to the lower portion, that is to say, the cathode 7 surrounds the filament 6 and is spaced therefrom, such cathode being carried by suitable ribs or flanges formed upon the member 37, as shown in Figure 2. This cathode is also supported by relatively rigid members 45 which connect with the conductor 43 carried within the glass standard 42. The anode 8 of this current limiting device surrounds the cathode 7 and is spaced therefrom. It is also carried by suitable rigid members 46 and 47 which join a central conductor 48 located in a second glass standard 49 carried from the base of the apparatus. 95 100

If found desirable the filaments 2 and 5 may be wound first in one direction and then in the other direction so that each filament is composed of two reversely wound sections so as to avoid any transformer action 105 in the apparatus. In regard to these filaments, it may be noted that one of the conductors, as indicated at 50, passes upwardly to a relatively stiff supporting member and to the lower end of the filaments. The upper end of the lower filament is connected to the lower end of the upper filament by conductor 20 and the upper end of the upper filament may be connected to a conductor 51 which extends through the upper end of the supporting member 37 and downwardly 110 through the supporting standard 36, as 115 shown in Figure 2. 120

It is to be distinctly understood that the precise mode of mounting these different elements and of supporting them may be varied without departing from the spirit of this invention, for instance circular or other forms may be substituted, and it is intended, therefore, that this detailed de- 125

scription of a physical embodiment of the tube is to be interpreted as illustrative rather than limiting.

Figure 3 showing a further form of the invention will now be described. In this figure, the apparatus is shown as connected between an input circuit and an output circuit. For instance, the input circuit may be electro-magnetically connected with the 10 device by means of the primary 52 and the secondary 53 of a transformer, and the output may similarly be electromagnetically connected with the apparatus by means of the primary 54 and the secondary 55 of a 15 transformer. Obviously, these transformers may be either audio frequency or radio frequency transformers and the device may be used either in a wireless receiving system or a telephone repeater circuit, and in 20 fact, in other similar capacities.

The device comprises a highly evacuated vessel or tube 56 within which the devices are located. The rectifying portion of the apparatus comprises a plate 57 and an equipotential cathode 58 heated by a filament 59. The wave filter or current limiting device is separated from the rectifier by means of a partition 60 of suitable material which comprises a plate 61 and an equipotential 25 cathode 62 heated by a filament 63. This wave filter is separated from the amplifier or detector by means of a partition 64. This detector or amplifier comprises a plate 65, a grid 66 and an equipotential cathode 67 heated by filament 68. The filament 68 is controlled by means of a rheostat 69 and is connected directly across the alternating current mains 11. The filaments 63 and 59 are connected in series and controlled by a 30 rheostat 70 and are connected across the mains. Obviously, these filaments might be in parallel and separately controlled or, if desired, the filaments may be lighted from the secondary of a transformer, as previously 35 described.

The primary 71 of a transformer provided preferably with adjustable taps is connected across the alternate mains 11-11. The secondary 72 preferably steps the voltage up and has one of its ends connected with the plate 57 by means of conductor 73. The cathode 58 of the rectifier is connected to the plate 61 of the filter by means of conductor 74. The cathode 62 of the filter is 50 connected by means of conductor 75 to the positive end of the unitary resistance 76. The negative end of this resistance is connected to the other terminal of the secondary 72. A condenser 77 may be connected between the last mentioned terminal of the secondary 72 and the conductor 74. This unitary resistance 76 is provided with any number of taps and suitable slidable or adjustable connectors cooperating with 55 the taps may be provided. One of such

members 78 is shown and is connected with one terminal of the primary 54 of the output transformer. The other terminal of the primary is connected to the plate 65 of the audion, as shown in Figure 3.

The operation of this apparatus is as follows:—The filaments are suitably adjusted and it is assumed that radio signals are being received. The current from the secondary 72 of the main transformer is rectified by the action of the cathode 58 and anode 57 of the rectifier and is delivered as a pulsating current along conductor 74,—the condenser 77 storing up energy between successive pulsations and serving to supply a more uniform current to the plate 61 of the current filter. From the plate 61 current passes to the cathode 62 of the filter and from thence by means of conductor 75 to the positive terminal of the resistance 76. This current passes through the resistance and to the opposite terminal of the secondary 72 of the main transformer. Current is drawn from any point along the resistance 76 at which the desired voltage is secured and passes through the primary 54 of the output transformer to the plate 65 of the detector or amplifier. From this plate the current passes to the equipotential cathode 67,—such flow between the plate and the cathode being controlled by the grid 66. From this cathode the current passes by means of conductor 78 to the negative terminal of the resistance 76. It will be noted from Figure 3 that the conductor 78 is also connected to one terminal of the secondary 53 of the input transformer, and that the other terminal of such secondary is connected to the grid 66.

It is, of course, understood that dielectric oxides may be used to coat the inner side of the cathodes, for example, these oxides may be nickelous oxide if desired. The outer side of the respective cathodes 67, 62 and 58 may be coated with barium, strontium, thorium or other electron emitting oxides upon the sides presented towards their respective plates. In this last described form of the invention each of the elements is called upon to perform only a single duty as distinguished from the form described in connection with Figure 1 in which certain of the elements perform a double duty. In this form of the invention the three main portions of the device would be carried in succession upon a central core such as illustrated in Figure 2 and the entire active portions of the device would be enclosed within the vessel 57 which would be highly evacuated. Although it is, of course, within the province of this invention to vary the degree of exhaustion of the vessels and also to vary the inert gas or vapor used.

Figure 4 shows a still further form of

the invention and will now be described. In this form the device is shown connected with the adjustable terminal of an inductance 79 of a radio receiving system, and at the other end with a telephone receiver 80 or equivalent device. It is to be distinctly understood, however, that this form may be used in other capacities as previously described, and that the showing in this figure is as in the previously described figures merely an illustration of one mode of use of the apparatus. In this form of the invention the devices are mounted in an evacuated vessel 81 which is divided by the partition 82, as previously described. In this form a pair of filaments 83 and 84 are provided and are connected in parallel and across the mains 11. They are independently controlled by rheostats 85 and 86, respectively. These filaments respectively heat the equipotential cathodes 87, and 88 and 89. It is to be noted that the cathodes 88 and 89 are both heated by the filament 84 and these cathodes as well as the corresponding plates 90 and 91 may surround opposite sides of the filament 84, as described in my above noted copending application. The detector or corresponding portion of the apparatus is provided with a grid 92 and with a plate 93,--the grid being connected through a suitable grid condenser and leak to one side of the inductance 79 in the customary manner,--the plate 93 of such apparatus being connected to the telephone receiver 80.

In this form of the invention the primary 93 of a transformer is connected across the alternating current mains and one end of the secondary 94 is connected with the plate 91 of the rectifier.

Current from the rectifier passes through conductor 95 to the condenser 99 and charges such condenser with its upper side positive. This condenser discharges through the choke coil 96 to the plate 90 of the current filter, from thence to the cathode 88 thereof and passes to the positive terminal of the unitary resistance 97 and, thereafter, to the other side of the condenser and to the other side of the transformer winding 94.

It will be noted that the condenser 99 and the choke coil 96 aid in smoothing out fluctuations prior to the delivery of current to the filter. Thus, it will be seen that a steady current is furnished by this apparatus and is passed through the resistance 97. The negative end of this resistance is connected by means of conductor 100 with the cathode 87 of the detector and such conductor may be extended and connected to the lower end of the inductance 79 through suitable adjustable taps. As stated, one side of the telephone receiver 80 is connected to the plate 93 of the detector, the other side of the receiver is connected by means of conductor 101 with any suitable point along

the resistance 97 to secure the correct voltage for the plate 93. Obviously, a telephone condenser 102 might be used if desired.

The current in the detector circuit passes through the receivers to the plate 93 and from the plate to the cathode 87 of such detector,--the flow of current being controlled by the grid 92 in the usual way. Current from the cathode 87 passes by means of conductor 100 to the negative terminal of the resistance 97.

It is to be understood that suitable oxides may be used in this form of the invention, as previously described, for instance, the sides of the cathodes 89, 88 and 87 presented towards the filaments may be coated with nickelous oxide and the sides of such cathodes presented toward such plates may be coated with any of the electron emitting oxides previously mentioned.

In all forms of this invention the proportioning of the surface of the rectifier and filter to that of the audion or equivalent device is to be determined in accordance with the particular work for which the apparatus is designed. For instance, if the apparatus is to be used in its unitary capacity without connection to other tubes or to loud speakers then the proportioning of surface of the active elements in the rectifier and filter may be just sufficient to supply the needs of the amplifier or detector. On the other hand, obviously, the apparatus may be used to energize other tubes or to energize loud speakers. In this case the proportion of the surface of the active elements of the rectifier and filter to that of the amplifier and detector is in excess of the needs of such amplifier or detector, so that the rectifier and filter may supply other translating devices such as tubes, loud speaker, and other similar apparatus.

It will be seen that a unitary device has been provided which may be energized directly from commercial alternating current mains, and that this device may serve as a wireless receiving apparatus or as an amplifier or as a repeating device for telephone or radio systems or in similar capacities.

It is to be distinctly understood that the terms used in the claims are to be interpreted in a general or inclusive manner, and that the expression "radio reception" or similar expressions are to be understood as including a detector or an amplifier for either wireless work proper or for telephone repeating systems or similar devices.

Although the invention has been described in considerable detail, it is to be understood that the invention may be variously embodied and is, therefore, to be limited only as claimed.

I claim:

1. A unitary electron discharge device in-

cluding an equipotential cathode, a plate cooperating with said cathode, a grid interposed between said cathode and said plate, a thermionic rectifier for supplying said plate, and a thermionic current limiting device controlling the current supplied said plate.

2. A unitary electron discharge device including an equipotential cathode, a plate 10 cooperating with said cathode, a controlling grid interposed between said cathode and plate, a filament for heating said cathode, said filament and cathode constituting a thermionic rectifier, a second heated cathode, and a second plate cooperating with 15 said second cathode and constituting therewith a thermionic current limiting device.

3. A unitary electron discharge device including an equipotential cathode, a filament 20 for heating said cathode and forming therewith a thermionic rectifier, a plate cooperating with said cathode, a controlling grid interposed between said plate and cathode, a second cathode, a second filament for heating said second cathode, and a second plate 25 cooperating with said second cathode and forming therewith a thermionic current limiting device.

4. A unitary device for receiving radio 30 waves including a thermionic rectifier consisting of a filament energized from alternating current and an electrode mounted adjacent said filament, a plate spaced from said electrode, a grid interposed between 35 said electrode and plate, said electrode constituting an equipotential cathode with reference to said plate, and a thermionic cur-

rent limiting device interposed in the circuit of said plate.

5. A device for use in radio reception 40 comprising a thermionic rectifier consisting of a filament and an electrode mounted adjacent said filament, a plate spaced from said electrode, a grid interposed between said electrode and plate, said electrode constituting a cathode with reference to said plate, said plate being electrically connected to said rectifier, and a thermionic current limiting device controlling the current flow to said plate, said plate, electrode, grid, 50 filament and rectifier constituting a unitary device.

6. A device for use in radio reception comprising a thermionic rectifier consisting of a filament and an electrode mounted 55 adjacent said filament, a plate spaced from said electrode, a grid interposed between said electrode and plate, said electrode constituting a cathode with reference to said plate, said plate being electrically connected 60 to said rectifier, and a thermionic current limiting device controlling the current flow to said plate, said thermionic current limiting device consisting of a filament, a cathode heated thereby, and an anode, said rectifier, grid, plate and thermionic current limiting device constituting a unitary 65 device.

In testimony that I claim the foregoing I have hereunto set my hand at Milwaukee, in 70 the county of Milwaukee and State of Wisconsin

ARISTOTE MAVROGENIS.
